UNITED STATES PATENT OFFICE.

SAMUEL SHOESMITH, OF LONDON, ONTARIO, CANADA.

AIR MOISTENING AND COOLING DEVICE.

1,279,460.

Specification of Letters Patent. Patented Sept. 17, 1918.

Application filed December 13, 1917. Serial No. 206,905.

To all whom it may concern:

Be it known that I, SAMUEL SHOESMITH, a subject of the King of England, and a resident of London, in the Province of Ontario and Dominion of Canada, have invented a new and Improved Air Moistening and Cooling Device, of which the following is a full, clear, and exact description.

This invention relates to mechanical devices for tempering, humidifying or otherwise modifying the atmosphere of a building, such as a hospital, sick room or other place where people, either invalids or others, are in the habit of being domiciled.

15 Among the objects of the invention therefore is to provide an apparatus adapted to be located in a window frame or opening after either or both of the usual sashes are removed, said apparatus including means 20 for causing a spray or mist from a quantity of water, either in natural state or charged with sea salt, medicaments or other chemicals, according to the requirements of the patients or other people within the building 25 or as prescribed by a physician.

More definitely stated my improvement contemplates the employment of a frame 30 adapted to be located in a window opening through an outside wall of the building, said frame having journaled therein upper and lower rollers over which an endless belt is caused by any suitable power means to roll at a relatively high speed, the outer run of the belt moving upwardly from a receptacle 35 at the bottom of the frame which contains any suitable fluid to be sprayed or atomized, and said belt serving not only to convert the fluid into a spray or mist, but also to carry the same over the upper roller into 40 the building for the purpose of so modifying the atmosphere of the building as to render the same more agreeable or conducive to the requirements of the inhabitants or patients thereof according to the climate 45 or other natural atmospheric conditions.

Another object of the invention is to provide improved facilities for mechanically modifying the atmosphere of a living room or hospital as to make the same conform, even in hot summer weather, to the climate at a salubrious seaside resort, and hence by this device I am able, in effect, to bring a suitable climate, so to speak, to the patient who may be unable financially or otherwise to go to a suitable climate.

With the foregoing and other objects in

view the invention consists in the arrangement and combination of parts hereinafter described and claimed, and while the invention is not restricted to the exact details 60 of construction disclosed or suggested herein, still for the purpose of illustrating a practical embodiment thereof reference is had to the accompanying drawings, in which like reference characters designate the same 65 parts in the several views, and in which

Figure 1 is a vertical sectional view indicating my improved apparatus placed in a window opening in the outer wall of a building, the view being on the line 1—1 of 70

Fig. 2.

Fig. 2 is an inside view of the belt portion of the improvement, parts being broken away or omitted to show particularly the belt construction.

75

Referring now more particularly to the drawings I show a wall 10 having a window opening of any suitable or conventional size or form 11 and from which the window sashes are removed. 12 indicates a rectangular frame fitted into the opening and secured therein in place of the usual sashes, and hence substantially filling said opening 11. Said frame includes upper and lower bars 13 and 14 as well as side bars 15 and 16. 80 85

Secured in or otherwise supported upon the lower portion of the frame is a trough-like or open topped receptacle 17 made preferably of a suitable rust-proof material of a substantial or permanent nature, and located 90 within and longitudinally of this receptacle is a lower roller 18 having bearings in the ends of the receptacle. This receptacle is adapted to contain a quantity of a suitable liquid such as water either in its natural 95 state or preferably charged with sea salt, medicaments or other chemicals according to the conditions to be met or complied with by the practice of the invention.

In the upper end of the frame and journaled preferably in the upper ends of the side bars 15 and 16 is a roller 19 having its axis parallel to the axis of the lower roller 18. Mounted upon the rollers is an endless belt 20 of any suitable flexible and preferably impervious material. The belt approximately fills all the hole space laterally between the side bars 15 and 16 of the frame and vertically between the two rollers. The belt, therefore, in its movement around the 110 rollers operates through the liquid in the receptacle 17. I provide, however, a substan-

tial space of say about six inches for an ordinary construction between the upper roller and the top bar 13 of the frame as indicated at 21.

5 One of the rollers, the upper roller as indicated, is provided with a pulley 22 or its equivalent, the pulley being arranged between the edge of the belt and the adjacent side bar of the frame. Said pulley represents a suitable transmission means for the rotation of the roller to which it is connected and hence the operation of the belt around both rollers at high speed. As a power means for operating this pulley I 10 show a rotary motor M to the shaft of which is secured one of a series of pulleys of various sizes, the one being selected that will provide the desired rate of speed for the manipulation of the belt for the best service. 15 This pulley on the motor shaft is indicated at 23 and a belt 24 operates over the two pulleys 22 and 23 for the purpose indicated. It will thus be seen that the belt is so operated that the outer run thereof will move 20 upwardly from the liquid in the receptacle and inwardly over the upper roller and thence down again to the receptacle.

The outer surface of the belt is provided in any suitable manner with a peculiar arrangement of ribs, buckets or flights 20'. These may be formed of the same material as the belt or any suitable material of a flexible nature so that the free movement of the belt shall not be impeded. These ribs or flights are each indicated in the form of an inverted V on the outer run or active side of the belt. In other words the apex portion of the rib moves in advance of the other portions upwardly through the liquid. 25 These ribs are secured upon the central portion of the outer surface of the belt and extend laterally and downwardly from said center toward the edges of the belt, stopping, however, short of the said edges. The liquid 30 that is picked up by these ribs as they are moved by the belt in rapid succession upwardly through the liquid will fall or flow both directly over the ribs and laterally and downwardly toward the ends of the ribs, 35 whereby a thorough mixture of the air takes place with the relatively minute portions or films of the liquid with the result that the air is charged with a maximum amount of moisture from the receptacle. As has already been indicated the belt is operated at 40 sufficiently high speed or the ribs are positioned so close together as to not only keep the liquid in a thorough state of agitation in the receptacle but also to cause substantial portions thereof to be carried upward from the receptacle in the form of spray or mist.

45 indicates a shield inclosing the upper and outer portion of the frame 12 and hence 50 shutting off all communication from the out-

side of the building direct to the upper part of the frame. The shield 25 may extend down toward the lower end of the frame to any desired distance, but indicated herein as extending down practically half way, but adjustably connected to the shield is a regulator 26 which in effect constitutes an extension of the shield 25 lying in a plane parallel to the outer run of the belt and spaced outwardly therefrom to provide a 55 channel 27. The lower edge of the regulator may be spaced at any desired distance from the upper outer edge of the receptacle as indicated at 28 into which space and upwardly through the channel a strong blast of 60 fresh air is caused to circulate from outdoors. This blast of air is forced over the upper roller 19 into the building or room at the top of the frame. Consequently the mist, spray or analogous means for charging the 65 blast of fresh air with the climatizing properties above indicated will become effective at the space 28 and along the channel 27. 70 29 indicates a baffle board located within the frame adjacent to the upper end thereof and 75 inclined downwardly and outwardly, the lower edge of the baffle board extending across between the side bars 15 and 16 and being arranged preferably directly above the inner edge of the receptacle 17. This 80 baffle is so located that any liquid particles carried up by the blast of humid air that tend to fly off from the belt at a tangent as the belt turns around the upper roller 19 will be received upon the baffle board whence 85 they will flow back into the receptacle. The major portion of the mixture, however, carried up by the blast will be disseminated throughout the building or room, any suitable outlet not shown being provided in the 90 room at some point remote from this apparatus to provide sufficient circulation of air for the purpose of the apparatus. It will thus be seen that while the liquid is carried up from the receptacle by the ribs or flights 95 100 105 110 115 120 125 130

I claim:

1. The combination with an outer wall of a building having a window opening therethrough, of a portable frame fitted in said opening, a receptacle for liquid in the lower portion of the frame, a roller journaled in said receptacle, a roller journaled adjacent to but spaced below the upper end of the frame, an endless flexible belt operating over said rollers with the outer run thereof moving upwardly from the receptacle, said belt being provided with a series of parallel V-shaped ribs the apexes of which move in ad-

vance of the ends thereof, and means to cause a blast of air to move upwardly with the outer run of the belt from the region of the receptacle to and inwardly over the 5 upper roller.

2. In a device of the character set forth, the combination of a frame, a roller journaled in the upper portion of the frame and spaced below the upper bar thereof, a receptacle for liquid below the upper roller, a lower roller journaled in the receptacle, 10 an endless belt operating over the rollers,

means to operate the belt at relatively high speed causing the same to carry films of the liquid from the receptacle, a shield carried by the outer portion of the frame adjacent to the upper roller to confine the spray, and a vertically adjustable regulator constituting an extension of said shield to variably control the blast of fresh air that 15 is caused to circulate upwardly within the shield above the receptacle.

SAMUEL SHOESMITH.
